Primary Examiner — Angela J Lee(74) *Attorney, Agent, or Firm* — Potomac Patent Group PLLC(57) **CLAIM**

The ornamental design for a user interface for a display screen, as shown and described.

DESCRIPTION

The sole FIGURE is a front view of a user interface for a display screen showing our new design.

In the FIGURE, the word "Advertising" in broken lines forms no part of the claimed design.

1 Claim, 1 Drawing Sheet
